UNITED STATES PATENT OFFICE.

CHARLES EDWARD HAVILAND, OF LIMOGES, FRANCE.

DESIGN FOR A DISH OR SIMILAR ARTICLE.

SPECIFICATION forming part of Design No. 37,102, dated August 23, 1904.

Application filed July 23, 1904. Serial No. 217,870. Term of patent 7 years.

To all whom it may concern:

Be it known that I, CHARLES EDWARD HAVILAND, a citizen of the United States, residing at Limoges, in the Republic of France, have invented a new, original, and ornamental Design for a Dish or Similar Article, of which the following is a specification, reference being had to the accompanying drawings, forming a part thereof, in which—

Figure 1 is a top view, and Fig. 2 an edge

view, of a dish bearing and incorporating my design.

What I claim is—

The ornamental design for a dish or similar article, substantially as shown.

CHARLES EDWARD HAVILAND.
